UNITED STATES PATENT OFFICE.

FREDERICK C. WARNE, OF MANSFIELD, OHIO, ASSIGNOR TO RODERICK LEAN MANUFACTURING COMPANY, OF MANSFIELD, OHIO, A CORPORATION OF NEW JERSEY.

HEAD FOR LAND-ROLLER DRUMS.

1,108,038.

Specification of Letters Patent.

Patented Aug. 18, 1914.

Application filed October 31, 1913. Serial No. 798,402.

To all whom it may concern:

Be it known that I, FREDERICK C. WARNE, citizen of the United States of America, residing at Mansfield, in the county of Rich-
5 land and State of Ohio, have invented cer-
tain new and useful Improvements in Heads
for Land-Roller Drums, of which the fol-
lowing is a specification.

This invention relates to heads for land
10 roller drums.

The object of this invention is to construct
a head for land rollers which will provide
means of preventing debris from entering
the drum of the roller and at the same time
15 afford facilities for painting or repairing
both sides of the head, as well as the inside
of the drum and to permit a free circulation
of air through the drum to obviate damp-
ness which results in corroding the parts
20 comprising the land roller; to construct a
substantially semi-open head for land rollers
with means of supporting a hub-bearing in
the center of the opening; to construct a
durable, rigid and simple head for land
25 rollers comprising a novel disk having a cen-
tral opening in combination with means to
support a hub-bearing in the center of said
opening; to provide means of connecting
and securely fastening the head to the drum
30 of the land roller.

A further object of this invention is to
provide a simple construction of a head that
will permit all of the parts comprising the
head to be made of pressed steel or the like.

Having these and other objects in view
35 the invention is illustrated in the accom-
panying drawing, in which:—

Figure 1 is a front elevation of part of a
land roller drum showing a part of the drum
40 broken away to show a vertical section of
the head and its application to the drum.
Fig. 2 is an outside or end view of the head,
drum and connecting parts. Fig. 3 is a side
elevation of the hub-bearing showing a frag-
45 ment of one of the radial supporting bars
fitted to the hub.

In the drawing reference numeral 1 indi-
cates a drum of a land roller of a well
known type to which the improved head is
50 applied.

In the construction of the head I use a
disk 2 which is provided with a peripheral
flange 3 and a bead 4 which surrounds and
forms the margin of the central opening 5.
55 The flat portion of the disk is preferably

made of such dimensions as to substantially
close one half of the opening in the end of
the drum leaving the opening 5 which per-
mits the free circulation of air into the drum
and affords facilities for repainting and re-
pairing both sides of the head and inside of
the drum. To mount the drum upon a suit-
able axle (not shown) a hub 6 having a
bearing 7 and an annular collar 8, is pro-
vided. Radial bars 9 are securely fastened
60 to the disk 2 on one end by the rivets 10.
The opposite ends project radially across the
opening 5 and are securely fastened to the
collar 8 of the hub-bearing by the rivets 11.
I have shown the bars made channel shape
65 with one end fitted to grooves 12 formed in
the collar 8. It will be understood, however,
that any form or size of bars can be used
without departing from the spirit of the in-
vention. The disk 2 is fastened to the
70 periphery of the drum by rivets 12' which
pass through the drum and the peripheral
flange 3.

It will be apparent that a head for a land
roller constructed as hereinbefore described
will permit of easy access to the inside of
the drum for any purpose, whatever, and
permit the free circulation of air there-
75 through, which would be prevented if the
drum was made solid and it will, also, be
noted that efficient strength, rigidity and
durability of the head are secured and pre-
80 served by means of its novel construction.

What I claim:—

1. In a pressed steel head for land rollers
comprising a disk with an open central por-
tion having a bead formed thereon adjacent
to and surrounding said open central por-
tion and a flange extending outwardly from
90 the periphery of said disk, a hub, means to
connect said hub to said disk and support
it in a central position with reference to the
opening in said disk as described and set
forth.

2. A head for a land roller drum made of
95 pressed steel comprising a disk having a
peripheral flange formed integral therewith
to provide means for fastening it to the
drum and also provided with a central open-
ing and a bead formed on said disk adjacent
100 to said opening, a hub and means to main-
tain and support said hub in a central posi-
tion with reference to said disk as described
and set forth.

3. A head for the drum of land rollers 110

comprising a disk made of pressed steel and formed with an outer peripheral flange and an inner peripheral bead, a hub, and means to support said hub centrally of said disk as described and set forth.

4. A head for the drum of a land roller comprising a disk provided with a central opening substantially half the diameter of the disk, and an outer peripheral flange, a hub, radial bars to support said hub in said

opening, and means to strengthen the disk on the margin surrounding said opening as described and set forth.

In testimony whereof I affix my signature in presence of two witnesses.

FREDERICK C. WARNE.
